United States Patent

Des. 237,788
Patented Nov. 25, 1975

237,788

SAILBOAT SPREADER FENDER

Blair E. Howe, 2121 Union Ave, Costa Mesa, Calif.
92627, and Kenneth J. Booth, 912 Lantana, Brea, Calif.
92621

Filed May 6, 1974, Ser. No. 467,219

Term of patent 14 years

Int. Cl. D12—99

U.S. Cl. D12—70

FIG. 1 is a perspective view showing the top, front and right side of the sailboat spreader fender;

FIG. 2 is a left side elevational view thereof;

FIG. 3 is a rear elevational view thereof; and

FIG. 4 is a bottom elevational view thereof.

We claim:

The ornamental design for a sailboat spreader fender, as shown.
